WOOD BURNING BROODER STOVE

John B. Olson and William M. Willett, Fort Atkinson, Wis., assignors to James Manufacturing Company, Fort Atkinson, Wis., a company

Application December 23, 1937, Serial No. 181,363

4 Claims. (Cl. 126—58)

This invention relates to an improvement in brooder stoves which are especially adapted to burn wood. The objects of the invention are to provide a stove proper, suitable for this and other purposes which has an improved operating and controlling means to thereby provide maximum efficiency and accuracy of control.

In a stove of the class it is desirable and economical to have the least possible fire while still holding the temperature constant. Wood burns readily when too much air is admitted, therefore in a burner wherein the fuel is replenished infrequently, the controlling device must be positive and accurate as to the quantity of admitted air and it must be sensitive to temperature changes.

It is an object of the present invention to reduce the fluctuation of temperature to a minimum by the use of positive and sensitive air and stack gas control in combination with a feeding door and an ash door which are practically airtight.

A further object of the present invention is to provide a stove proper or housing having very few joints which may be made practically airtight.

A further object of this invention is to provide means whereby the air for combustion is furnished to the center of the chamber by means of an inverted channel and a comparatively small grate which is centrally positioned a distance above the bottom of the housing whereby a considerable accumulation of ashes on the bottom around the grate and channel will not shut off the supply of air to the grate.

One of the principal objects of the present invention is to provide convenient means for stacking and holding the wood toward the center of the chamber, so that the wood will burn from the center outwardly, cooperating with an ash door which provides access to the entire bottom of the chamber whereby excessive ashes may be removed from around the grate or from under the grate and from the channel.

One of the contributing factors to the successful operation of our invention is the manner of controlling the air supply to the grate in combination with a chimney check valve and a chimney choke valve each being adapted to be operated simultaneously but oppositely by means of a connection to the thermal device, whereby satisfactory results may be secured from the burning of wood under all atmospheric conditions and under varying chimney drafts.

To these and other useful ends our invention

consists of parts and combinations thereof or their equivalents and mode of operation as hereinafter set forth and claimed and shown in the accompanying drawings in which:

Fig. 1 is a vertical transverse section of our improved device taken on line 1—1 of Figure 2.

Fig. 2 is a vertical section of the device taken on line 2—2 of Figure 1.

Fig. 3 is a fractional section of the device taken on line 3—3 of Figure 5.

Fig. 4 is an enlarged fractional section of the device taken on line 4—4 of Figure 1.

Fig. 5 is an enlarged fractional section of the device similar to that shown in Figure 2 except illustrating a modified thermal controlling device.

Fig. 6 is a fractional enlarged section taken on line 6—6 of Figure 7.

Fig. 7 is a section taken on line 7—7 of Figure 2.

As thus illustrated we provide a chamber having preferably a parallelogram shape horizontally and vertically, the vertical walls of the chamber being designated by reference numerals 10, the bottom of the chamber being designated by numeral 11 and the top by numeral 12. These members 11 and 12 are secured to the side walls 25 by means of a folded joint or by interval welding as at 13 (see Figure 3).

Thus it will be seen that the inclosure may be rectangular in cross section, square, round, oval or any suitable shape and may be manufactured at low cost and in a manner which will provide a strong and air-tight inclosure.

We provide legs 15 which, when the inclosure is square or rectangular, are secured to the corners of the closure and are made of a sufficient length so as to hold member 11 a proper distance from the floor so as to provide suitable ranging room for the chicks.

We provide preferably three hover members 16 which are positioned and made of a shape to correspond with the shape of the chamber; thus these members may be secured together and supported by the chamber as at 17. Rear member 16A is preferably detachably secured to the chamber and to side members 16.

Thus we have provided a simple, light and easily manufactured hover which is easily positioned around the stove and whereby the controlling mechanism and the ash door are made accessible by simply removing one section of the 50 hover.

We provide a grate 18 which is positioned in the inclosure as illustrated and having a rearwardly extending plate 19 each having downwardly extending flanges 20 and 21 and member 55

19 being secured to member 10 as at 22. The free end of the grate is supported on member 11 by means of legs 23.

5 A housing 25 (see Figure 2) is secured to member 10 forming a cover to inlet opening 26 in member 10. This housing is shaped as illustrated so as to provide an air inlet opening 27 and an ash door opening 28. Housing 25 is provided with a rearwardly extending arm 29 having a 10 lever 30 which is hingedly supported at its rear end to member 29 by means of a bolt 31.

We provide the usual thermal control wafer 32; thus by adjusting bolt 31 lever 30 may be controlled directly by wafer 32 to operate the dampers and control the fire in the chamber as follows:

15 A valve 35 is pivotally mounted to housing 25 as at 36 and is provided with a link connection 37 to lever 30; thus the position of lever 30 will control the opening 27 by means of valve 35.

20 We provide a chimney housing 40 being adapted to support the usual stove pipe 41. We provide an opening 42 in the top of member 12 and an opening 43 is also provided in the rear of member 40. A lever 44 is pivotally supported in a notch 25 formed in member 40 as at 45. This supporting means is in reality a valve 46 which is adapted to cover opening 43 more or less, depending upon the position of lever 44. The forward side of valve 46 is provided with a forwardly extending lever 25 47 having at its end a hook 48.

We provide a valve 49 which has a loop 50 which is adapted to be freely supported by hook 48. Thus it will be seen that as the rear end of lever 44 is lowered, valve 46 will open inlet 43 and 35 lever 47 will be caused to close valve 49. Thus opposite motions are imparted to the valves simultaneously by means of lever 30 through a link 51. Thus by scrutinizing Figure 2 it will be seen that wafer 32 will control the position of these 40 three valves simultaneously and that when valves 35 and 49 are closed valve 46 will be open. That is, when wafer 32 is expanded so as to call for less heat, valves 35 and 49 will be closed and valve 46 will be opened so as to reduce the vacuum 45 in the stove chamber caused by chimney 41. It is not desirable to entirely close opening 42; we therefore provide an orifice or two in valve 49 so at all times there may be passage of gases into the chimney even though the air is positively 50 prevented from entering the stove.

Thus it will be seen that we have provided a three point control wherein the chimney draft will be reduced almost to zero by means of a check draft inlet when the grate air is entirely 55 shut off and that the chimney inlet from the stove chamber will be practically shut off at a time when the check draft is open. Thus the vacuum in the housing will be practically zero when the temperature under the hover has 60 reached maximum and when the temperature under the hover has fallen below the desired amount the valves may finally reach a point when the inlet to the grate is wide open, valve 49 is wide 65 open and valve 46 is closed thus to create maximum draft.

We provide means in member 12 for supplying fuel in the following manner:

An opening 60 is provided of sufficient size having therein an upwardly extending flange 61. A 70 flanged lid 62 is provided which is adapted to fit snugly over flange 61. We secure a flanged plate 63 to the bottom of member 62 providing an air space 64 thus to provide a heat insulating 75 lid for the top of the stove.

We secure U shaped brackets 65—65 to member 12 as illustrated and secure bar 66 to the top of member 62 by means of a spacing washer and a rivet 67, the bar being left free to turn on the rivet and spacing washer. 5

A hand piece 68 is provided. Member 66 is adapted to extend under the upper portion of member 65 as illustrated, this portion being slightly lower than the ends of member 66; thus when the lid is placed over the opening and pressure is applied to member 68, which may then be turned so the ends of member 66 are under the upper ends of member 65. Thus lid 62 will be caused to firmly engage flange 61 as clearly illustrated in Figure 7. Thus the lid will be held 10 snugly in position and practically form an airtight seal. 15

In Figure 5 we illustrate a modified form of temperature controlling device being positioned near the stove thus to be suitable for use without the hover, wherein a supporting arm 70 is provided, having a U shaped bracket 71, a link 72 and a lever 73 to which link 37 is attached as illustrated. 20

We provide a rod 74 which is pivotally secured 25 to lever 73 as at 75, the rod extending through member 70, the end being adapted to support wafers 76, the wafers in turn being secured to a rod 77.

We provide a U shaped bracket 78 through 30 which rod 77 extends. Rod 77 is threaded for the reception of adjusting nut 79. We provide a washer 80 which supports nut 79 against the pressure of spring 81. Thus nut 79 may be turned in order to secure the desired temperature 35 through expansion and contraction of the wafers.

In Figures 1 and 2 we illustrate the chamber as having been supplied with ashes for the purpose already described. It will be seen that the 40 ashes will direct all of the air to the grate and that they will provide a suitable insulating material for the bottom of the stove and a suitable support for an accumulation of wood in the 45 stove.

We provide a lid 82 of a suitable shape to close opening 28. Hooked rod 83 is loosely mounted in lid 82 as illustrated having a spring 84 whereby when the lid is placed into position over opening 28 member 83 may be pushed forward against 50 the pressure of the spring far enough to hook over bracket 85; thus lid 82 will be spring held against the opening in member 25. When it is desired to remove ashes or to clear the grate, lid 82 is removed and a suitable rake used for the 55 purpose.

It will be seen by observing the various figures that this rake may be made long enough and have a shape at its end to reach practically every part of the inclosure; thus obviously it is 60 a simple matter to remove surplus ash and clear the grate and air passageway under member 19.

Clearly we have provided a simple and efficient brooder stove, that may be manufactured at low cost, that will be under perfect wafer control. 65

Having thus shown and described our invention we claim:

1. A stove of the class described, comprising a rectangular in horizontal and vertical section chamber, a fuel inlet door and a chimney outlet 70 in the top of said chamber, a relatively small centrally positioned grate in said chamber having downwardly extending flanges on its sides, the bottoms of the flanges being spaced a short distance above the bottom of the chamber, an in- 75

- verted channel integral with or secured to said 5
grate and extending outwardly to one of the
walls of said chamber and being secured thereto
the flanges registering with the grate flanges, an
air inlet in said chamber positioned below said
channel and extending to near the bottom of
the chamber and being less in width than said
channel at its contact with said chamber wall,
an air inlet valve and an access door operatively
connected to said inlet, whereby the bottom of
said chamber around said grate and channel
may be covered with ashes to or above the top
of the grate and channel whereby a sealed air
passageway is formed from said inlet to said
grate.
2. A stove of the class described, comprising a
chamber, a fuel inlet door and a chimney outlet
in the top of said chamber, a relatively small
grate centrally positioned in said chamber hav- 20
ing downwardly extending flanges at its sides
the bottom edges of which are positioned a short
distance from the bottom of said chamber, an
inverted channel secured to or forming an in-
tegral part of said grate the flanges of which
register with the grate flanges, the outer end of
said channel being secured to the wall of said
- chamber, an air inlet in said chamber the top
registering with said channel and extending to
near the bottom of the chamber and being less
in width than the width of said channel at its
contact to said chamber, an inlet air valve and
an access door operatively connected to said in-
let, whereby said chamber around said grate and
channel may be covered with ashes to or above
the top of the grate and channel to thereby form
a sealed air passageway within said channel 10
from said inlet to said grate.
3. A device as recited in claim 2 including;
draft controlling check valves in said chimney
outlet, thermally controlled means operatively
connected to said inlet valve and to said check 15
valves whereby combustion will be automatically
controlled.
4. A device as recited in claim 2 including;
relatively slender supporting means secured to
the free end of said grate and resting on the 20
bottom of said chamber thereby leaving substan-
tially the entire bottom of said chamber free for
contact with a poker which may be inserted in
said air inlet.

JOHN B. OLSON.
WILLIAM M. WILLETT.
